UNITED STATES PATENT OFFICE

109,246

DESIGN FOR A DOUCHE BAG COVER

Ethel E. Kinney, Seattle, Wash.

Application January 28, 1938, Serial No. 74,689

Term of patent 3½ years

To all whom it may concern:

Be it known that I, Ethel E. Kinney, a citizen of the United States, residing at Seattle, in the county of King and State of Washington, have invented a new, original, and ornamental Design for Douche Bag Covers, of which the following is a specification, reference being had to the accompanying drawing, forming part thereof.

I claim:

The ornamental design for a douche bag cover, substantially as shown.

ETHEL E. KINNEY.
